[57] ABSTRACT

An apparatus for wrapping stacked compressible materials in thermo-shrinkable plastics film and capable of operating in a continuous sequence on consecutive stacks. The apparatus having a wrapping, a heating and a cooling station provided respectively, with lower first, second and third consecutively aligned roller conveyors, which are at the same level and are driven independently at desired times to convey a stack into and out of each station in turn and halting the stack in each station for a desired period. Each station is provided with an upper press member having an upper conveyer mounted on its underside driven in synchronism with the corresponding lower conveyer. The upper conveyers at the heating and cooling stations are maintained at the same level as the upper conveyer at the wrapping station so that the compression of the stack achieved at the wrapping station is maintained at the other two stations during the film shrinking process.

APPARATUS FOR WRAPPING STACKED
COMPRESSIBLE MATERIALS IN A
THERMO-SHRINKABLE PLASTICS FILM

The present invention relates to an apparatus operating in a continuous sequence for wrapping stacked compressible materials in a thermo-shrinkable plastics film.

It is known that thermo-shrinkable plastics materials are available in the form of films facilitating an automatic and rational operation for wrapping products supplied for sale, the advantages of which are, inter alia, a saving in the cost of the materials used, a reduction in the labor cost, a visible presentation of the product, storage and transportation out of doors without any fear of the action of ambient humidity. This method of wrapping has been decided on for compact and non-deformable products, of any shape, by means of appropriate thermo-shrinkable plastics films. As regards compressible materials, or materials subject to the phenomenon of expansion when moist, such as paper, cardboard, paper or cardboard folded boxes, fibres, textiles, corrugated cardboard or any product able to be stacked, with or without a palette, the solution of the packaging problem required a preliminary operation of pressing said product, then keeping it at a reduced volume during the shrinkage of the cover as well as during its cooling.

Current techniques offer apparatuses characterised by the arrival of products which have not been pressed, already wrapped in their cover, along a feed path having freely rotating or motorized rollers, which guide them to a press plate. Said press is mounted on a carriage also provided with freely rotating or motorized rollers, which is able to move the press arrangement and pressed products along an axis perpendicular to the axis of translation of the roller path. At the end of the operation, the press and the products are introduced into a heating oven. After a predetermined period of time, the oven is opened and the carriage leaves the oven to allow the cover to cool. The last operation is that of raising the press plate for discharging the products onto the discharge roller path in order to obtain the desired result, namely: products which are perfectly wrapped by a cover which is in close contact therewith.

A first drawback of this apparatus resides in the fact that the various operations of pressing, heating and cooling are effected in perpendicular directions.

In fact, the press and products are brought into the heating oven by means of a second roller path perpendicular to the former. Due to this, after passing into the heating oven, the press and products are once more displaced on the second roller path and kept on one of the roller paths for the time necessary for cooling, the press only being released after complete cooling of the plastics envelope. A new cycle of placing the load under pressure and moving it into the heating oven may only take place when said press has been released.

There is thus a considerable period of time during which the press and other members such as the heating oven are inoperative, which does not facilitate continuous packing of the loads to be wrapped.

Moreover, the fact of introducing the press into the heating oven forces the designer to provide an oven of considerable volume to facilitate the introduction of the different presses whose heights vary.

Another drawback resides in the fact that said press is also partly subjected to the temperature prevailing inside said oven, which may damage the sensitive parts of the press.

5 Another drawback in apparatuses existing hitherto and in the non-automatic sequence of operations; is to place the product on a palette on roller paths located upstream and downstream and on the press carriage, the latter being provided with freely rotating rollers requiring the operator to undertake manual operations, the times of the various operations being left to the personal initiative of said operator; the rhythm and reliability of packing leaving much to be desired. Finally, the location of the electric control unit controlling the 10 pressing, heating, opening and closing of the oven doors, requires the operator to move about a great deal or makes a second operator necessary.

It is the object of the present invention to remedy the aforesaid drawbacks and to propose an apparatus capable of producing continuous wrapping of compressible products in a thermo-shrinkable plastics film, said apparatus being of the type comprising a station for pre-wrapping in the plastics film and for placing the compressible materials to be wrapped under pressure at the 15 desired value, an oven for heating the plastics envelope covering said materials to be wrapped and a cooling station in which the heated envelope is cooled to allow shrinkage of said envelope in order that it follows the shape of the pressed materials perfectly, characterised in that the various stations for pre-wrapping, heating and cooling are located in a line and in that the means for placing the materials under pressure are incorporated in the heating oven.

Owing to this, the various stages of pre-wrapping the 20 materials, heating the thermo-shrinkable wrapping film and cooling said plastics film may be carried out continuously. Thus, whilst heating the envelope of a stack of materials, it is possible to pre-wrap the next stack which passes into the heating oven after the discharge 25 of the preceding stack which is discharged into the cooling station where it is cooled during the heating of the stack admitted to the heating oven.

According to another feature of the invention, the 25 heating oven is variable in height and is constituted by two half-shells open at one of their sides and movable in an air tight manner with respect to each other.

Due to this, the height of the heating oven is adapted to the height of the stack of materials which makes it 30 possible to limit the production of hot air to the volume of the heating oven.

According to another feature, the stations for pre-wrapping, heating and cooling are constituted by rollers for conveying and supporting the materials to be wrapped, the rollers of each station being able to be rotated in synchronism with the rollers of another operating station such that the materials are displaced in a uniform manner and smoothly when passing from one working station to another. Due to the alignment of 35 said rollers in the same horizontal plane, the materials are always pressed at the same value.

Further features and advantages will become apparent on reading the ensuing description given as a non-limiting example and with reference to the accompanying drawings in which:

FIG. 1 is an elevational view of the wrapping apparatus according to one embodiment of the invention;

FIG. 2 is a plan view of the heating station.

FIG. 3 is a sectional view of the heating oven.

According to the embodiment illustrated in FIGS. 1 to 3, the apparatus is constituted by different working stations located in a line, connected to each other by sections of roller path constituting a single roller and support path whose various parts and functions will be described hereafter.

Station 1 comprising conveying rollers 6 rotated or not rotated is intended to receive a handling palette 9 on which is placed a stack of compressible materials 8. In this station 1 the stack 8 is wrapped by an envelop 10 of thermo-shrinkable plastics material known per se. The stack 8 covered by its envelope 10 without special precautions is brought into a station 2 for putting it under pressure, the conveying and support rollers 6a of which are firstly at the same level as the rollers 6 and secondly rotated by means of a reduction motor 7 and other parts known per se. Located in this station 2 is a press provided with a stand 11 and bracket 12, said press being able to displace along the roller path, i.e., perpendicularly to the generatrices of the conveyor and support rollers 6a; provided on the lower face of the pressure plate 15 are conveyor rollers 16 rotated by reduction motors 17, the upper rollers 16 and lower rollers 6a being driven in synchronism in manner known per se. The pressure plate 15 and rollers 16 being brought into contact with the top of the stack 8 covered with its envelope 10, their descent is controlled by means of a hydraulic cylinder device 13 controlled by a central station 14 so as to apply to said covered stack the desired pressure depending on the nature of the material to be wrapped and which, in the case of corrugated card or folding boxes is of the order of $1T/m^2$.

While the stack 8 is being placed under pressure, the envelope 10 is put in position so that the latter appropriately covers the materials displacing said envelope if necessary and, this is in order that at the time of the subsequent shrinkage of the plastics material, there are no parts of least resistance and parts where said envelope is not applied uniformly against the materials.

When the stack 8 has been placed under pressure, the latter is supplied by means of rollers 16 and 6a to a heating station 3 in which is provided a heating oven 19 provided with two doors 20 and 20a sliding in the direction of the generatrices of the rollers of the roller path. The oven 19 is constituted by at least two half-shells 30 and 31, in the shape of a U and able to be displaced with respect to each other in order to produce with the doors 20 and 20a, a vessel which is closed in an air tight manner by seals 32. Provided in the bases of the half-shells 30 and 31 are conveyor rollers 16a and 6b rotated by reduction motors 17 and 7 such that they rotate in synchronism with each other and with the rollers 16 and 6a of the pressure station 2. In this manner, the stack 8 passes from station 2 to station 3 continuously and smoothly. In addition, since the rollers 16a are strictly at the same level as the rollers 16 and since the pressure able to push the upper half-shell 30 onto said stack 8 is also equal to that exerted by the rollers 16 in the station 2, said stack is transferred from station 2 to station 3 under the same pressure. In this way, there is no tendency for the stack to expand between stations 2 and 3 and the heating of the plastics envelope 10 may be carried out appropriately, the stack 8 always being at the height that it must have after cooling.

Preferably, the rollers 16a are made of special plastics material which is resistant to heat or covered by an endless belt 18 made of a fireproof and strong material, for example a metal belt covered with a film of material known by the trade name "TEFLON." Similarly, said belt may be made of asbestos. This makes it possible to avoid direct contact between the rollers and the hot thermo-shrinkable envelope, which contact could cause adhesion and consequently tearing of the envelope. Moreover, this also makes it possible that the contact surface applied to said envelope is plane which gives the stack when cooled perfectly plane surfaces, at least, as regards the upper and lateral faces. Naturally, the lower rollers 6a may be protected in the same manner as the rollers 16a, which would give the stack arrangement perfectly plane walls.

In a preferred embodiment of the invention, the rollers 16a provided or not with their belt, are secured to the end wall of an internal sleeve 27, in the shape of an inverted U and housed inside the upper half-shell 30. The sleeve 27 partially surrounds the stack 8 and provides between its outer wall and the inner wall of said half-shell 30, an annular space 28 in which circulates hot pulses of air 23, provided with its burner 24 and blower 25. The hot air is channelled towards the stack 8 by means of an aperture 33 defined by the lower edge of the sleeve 27 and the lower curved edge 30a of the half-shell 30. The rollers 16a and the sleeve are displaced with respect to the stack 8 by any appropriate means such as a press similar to that provided in station 2. In this case, the sleeve 27 and the rollers 16a are integral with the press plate, the displacement of said press plate being effected along a stand and by means of a cylinder device associated with a hydraulic central station.

In order to improve the heating qualities and to reliably avoid the risk of adhesion of the pressure rollers 16a to the plastics envelope 10, the upper part of the oven and said rollers 16a may be cooled by means of an appropriate cooling circuit known per se and which has not been shown in order not to over burden the drawing.

After heating the plastics envelope in the heating oven, the rollers 16a and 6b are set in rotation, which causes the discharge of the stack 8 from said heating oven and towards a cooling station 4 in which is located a press similar to those described previously, the upper rollers 16b integral with the pressure plate and the lower rollers 6 of the roller path being rotated in synchronism with each other and with the rollers 16a and 6b, the rollers 16b and 6c being strictly at the same level as the rollers 16a and 6b respectively. The stack 8 always kept at the same pressure is displaced along the roller path from station 4 until the plastics envelope 10 is completely cooled, said cooling causing, in manner known per se, the shrinkage of said plastics envelope, which is thus applied against the entire surface of the materials such that the latter are appropriately wrapped and without any possibility of resuming their position before being placed under pressure, the wrapped materials being in the form illustrated in FIG. 1 in the discharge station 5 which is adjacent the station 4 and provided with rollers 6d which are driven or not driven and located at the same level as the rollers 6c.

Naturally, the various operations such as pressing, heating and discharge are controlled by an electric cir-

cuit not illustrated and not part of the invention. In fact, the apparatus according to the invention is associated with a central electronic control means which sets the various conveying rollers in rotation and which controls the opening of the doors 20 and 20a in the position illustrated in broken line in FIG. 3. Thus, while a stack 8 is being discharged from the heating oven 19, i.e., as soon as the stack 8 is displaced by the rollers 16b, another stack may be displaced by the rollers 16b to bring it into the heating oven 19 when said stacks have the same height.

In the case where the next stack to be heated is of a different height to that which is to be discharged from said heating oven, the central electronic control means only authorises the transfer from station 2 to station 3 when the stack being discharged is completely outside the heating oven 19, i.e., when it is in the cooling station 4. Moreover, when the height of a pressed stack is determined, the central electronic control means defines the position of the various rollers 16a and 16b such that the stack is transferred from one station to the other without the pressure applied thereto varying in any manner whatever.

Thus, the stoppages and starting up of the reduction motors 7 and 17 as well as the sending of hot air into the oven is programmed depending on the nature of the material to be wrapped. In the same manner, the time during which the plastics envelope is exposed inside the heating oven is variable. This is the reason why this variation is also programmed and controlled by the central electronic control means. We can thus see the progress made by the apparatus according to the invention, since the wrapping of stacks of any height may be undertaken continuously, said apparatus being capable of wrapping, in a given time, three times more than was possible with known apparatuses.

Naturally, the present invention is not limited to the embodiments described, but on the contrary extends to all variations. Thus, station 2 may be eliminated if the heating oven comprises members for positioning the envelope, which are able to be controlled from outside said heating oven. In fact, the station 2 for placing the stack under pressure is dispensable only if the heating oven is equipped with such members. If these members exist, the stack previously covered with its envelope may be sent directly into the heating oven, inside which the admission of hot air being interrupted, the stack is put under pressure at the desired value and the envelope is put in the correct position around said stack.

When this is completed, hot air is admitted in order to heat the plastics envelope, the remainder of the operations being unchanged.

What is claimed is:

1. A continuously operating shrink film wrapping apparatus comprising, in combination, a horizontal anti-friction conveyor means for supporting for advancement along a linear path, a pallet carrying an article to be wrapped, said article being covered by a shrinkable plastic film, a compression zone at an upstream position along said path, said zone including a planar pres-

sure plate means in parallel spaced relation to said conveyor means and shiftable toward and away therefrom for squeezing said article between said plate means and conveyor means, drive means on said pressure plate means for engaging the film portion above the upper surface of said article and advancing said compressed article along said path, a heating zone adjacent and downstream of said compression zone positioned to receive articles compressed at said compression zone, said heating zone including a second compression plate means in parallel spaced relation to said conveyor and shiftable toward and away from said conveyor, said second plate means including second drive means for engaging the film above the upper surface of said article and advancing said article in said direction, heating means at said heating zone for heating said film as the same traverses said zone, and a cooling zone along said path adjacent and in downstream relation to said heating zone, said cooling zone including a third compression plate means in parallel spaced relation to said conveyor, said third plate means including third drive means for engaging said film above the upper surface of the article emerging from said heat zone and advancing the same along said path, the spacing of said first, second and third drive means from said conveyor being substantially identical, whereby said article and film are subjected to a constant compressive force as the same traverse said path.

2. Apparatus in accordance with claim 1 wherein said heating zone includes a heat chamber, the upper surface of which is defined by said second drive means, said chamber including upper and lower, telescopically interfiting, vertically relatively movable half shells, said half shells having open portions at their upstream and downstream ends to permit passage therethrough of said article and film.

3. Apparatus in accordance with claim 2 wherein said heating chamber includes upstream and downstream door portions shiftable in a direction normal to said path between first and second positions, respectively, forming with said ends of said half shells a substantially air impervious enclosure, and in clearing relation of said ends.

4. Apparatus in accordance with claim 3 wherein said upper half shell includes an internal sleeve resistant to heat and adapted to be disposed about said article and film, said sleeve and upper half shell defining therebetween an annular space for the circulation of heated air.

5. Apparatus in accordance with claim 1 wherein at least one of said drive means comprises a plurality of rollers mounted on a said plate means, the lower peripheries of said rollers being in coplanar alignment, and an endless anti-friction belt arrayed about said rollers and having a lower flight engaged against said lower peripheries.

6. Apparatus in accordance with claim 5 and including means for directing a source of cooling fluid against said rollers.
